WINDOW VENTILATOR

Herman T. Stelljes, Hollis, N. Y.

Application March 14, 1936, Serial No. 68,805

7 Claims. (Cl. 98—97)

My invention relates to window ventilators and more particularly to the type built into or forming a part of sash portion of the window.

One object of the invention is to provide a simple and inexpensive construction which is easy to install, and which provides for adequate ventilation of a room while preventing entrance of rain and wind.

Another object is to provide a ventilator which is easy to manufacture, neat in appearance, and built into the bottom of a window sash so as to occupy no more space than the ordinary sash portion of a window.

A further object is to provide simple and efficient means for controlling the admission of air to the room through the ventilator.

Various other objects and advantages of the invention will be apparent as the description proceeds, and as illustrated in the accompanying drawing forming a part of this specification, and in which:

Fig. 1 is an outside or weather side of a window equipped with my improved ventilator.

Fig. 2 a view of the window showing the inside or room side of the ventilator construction,

Fig. 3 a cross-section on the line 3—3 of Fig. 2, and,

Fig. 4 a detail adjacent the bottom of the window sash.

In the drawing 10 indicates a window frame in which a sash 11 is mounted to slide, so that the window may be opened or closed in the usual way. I have combined ventilating features in the bottom portion 12 of the sash so that the window may occupy a normally closed position and be latched in the usual way as a protective measure to prevent unauthorized raising of the window sash.

It will be noted that the bottom of the window sash is provided with a series of openings 13 extending through the sash from the weather side 14 to the interior or room side 15 for the passage of air. Preferably the openings 13 are inclined upward from the weather side 14 as at 16 to aid in excluding rain which otherwise may be driven directly across the openings. Much of the rain which strikes the bottom surfaces of the openings 13 will drain from these inclined faces to the outside of the sash. Furthermore, I provide screens 17 which may be held in place over the openings 13 and against a recessed portion between the front and rear walls 19 and 20 of the sash as at 18. A plate 21 having apertures 22 opposite the openings 13 provides simple and effective

means for holding the screens in place. Fasteners such as screws 23 may be used for securing the plate over the screens and to the body of the sash. For controlling the admission of air to the room or for shutting off the supply entirely there is provided a door 24 which is swingably connected at 25 to the bottom portion of the sash 12. The sash is recessed as at 26 to receive the door 24 in its closed position against the openings 13, and a gasket or frame of felt or other suitable material 27 effects a tight joint against the door surface when the door is held closed by suitable means such as latch pieces 28 engaging over catch elements 29 attached to the free outer edge of the door. A handle or knob 30 may be provided for facilitating closing and opening of the door. The door may be held in various angular positions by means of an adjustable brace 31 so as to control and direct the supply of air entering the room. A suitable form of brace is that illustrated in Fig. 3 wherein a link 32 swingably connected to the door 24 is adjustably secured to another similar link 33 by means of a thumb screw 34, the other end of the link 33 being pivotally secured to a stationary bracket 35 mounted in a recess 36 in the sash between a pair of the openings 13.

Beneath the screens 17 there is a channel portion 37 formed in the body of the sash and which is adapted to catch drainage from the screens resulting from moisture or rain being driven thereagainst. The channel portion 37 extends across the sash beneath the entire series of openings 13, and has an exit or drainage port 38. Moisture or rain which may be driven through or off of the screens toward the interior of the room, as by a high wind, will fall onto the inclined upper surface of the door, which may be readily adjusted for the particular weather prevailing at the time, and will drain toward the channel portion 37 and over a deflector or bridge piece 40 extending the length of the door adjacent the hinged part of the door and then into the channel. It will be seen that the deflector 40 also protects the hinged connection 25 of the door from moisture which may drain from the screens. When the door is fully closed as in Fig. 4 the deflector 40 projects down into the channel portion 37 and provides the same protection at the bottom of the door.

It is to be understood that the invention as above described is not confined to the exact details of construction set forth, but is capable of being embodied in various other modified forms

of construction or variously altered within the scope of the appended claims. This includes any suitable form of metal construction or combinations of metal and wood or other materials utilizing the fundamental principles set forth in this specification.

Having thus described my invention, I claim:

1. A combined window sash and ventilator having openings for the passage of air, screens in the openings, a door at the rear of the openings for controlling passage of air therethrough, said sash having a lengthwise channel portion formed in the body of the sash beneath the screens, and a deflector carried by the door and adapted to extend downward into said channel portion for directing drainage into the channel portion, the latter having a port to the outside of the sash.
2. A combined window sash and ventilator having openings for the passage of air, screens in the openings, said sash having a lengthwise channel portion formed in the body of the sash beneath the screens, a door at the rear of the openings for controlling passage of air therethrough, said door being swingably connected to the sash adjacent the mouth of said channel portion, and a deflector carried by the door in a position to extend into and direct drainage into said channel portion, said sash having a drainage port communicating with said channel portion.
3. A combined window sash and ventilator having openings for the passage of air, screens in said openings, said sash having a lengthwise channel formed in the body of the sash beneath the screens, a door at the rear of the openings for controlling passage of air therethrough, said door being swingably connected to the sash adjacent the mouth of said channel portion, means for releasably holding the door closed over said openings, means for holding the door in an open position inclined downward toward the mouth of the channel, and a deflector associated with the door and adapted to extend into and direct drainage into said channel portion, said sash having a drainage port communicating with said channel portion.
4. A combined window sash and ventilator having openings for the passage of air, screens in the openings, said sash having a lengthwise channel portion formed in the body of the sash beneath the screens, a door at the rear of the openings for controlling passage of air therethrough,

said door being swingably connected to the sash adjacent the mouth of said channel portion, means for releasably holding the door closed over said openings, means for holding the door in an open position inclined downward toward the mouth of the channel, a deflector carried by the door and adapted to extend into and direct drainage into said channel portion, said sash having a drainage port communicating with said channel to the weather side of the sash, and a screen in said port.

5. A combined window sash and ventilator having openings for the passage of air, screens in the openings, said sash having a lengthwise channel formed in the body of the sash beneath the screens, a door at the rear of the openings for controlling passage of air therethrough, said door being swingably connected to the sash adjacent the mouth of said channel portion, means for releasably holding the door closed over said openings, weather strip around said openings for sealing the door in its closed position against the sash, said openings having surfaces inclined upward from the weather side of the sash, means for holding the door in an open position inclined downward toward the mouth of the channel, a deflector carried by the door and adapted to extend into and direct drainage into said channel portion, said sash having a drainage port communicating with said channel to the weather side of the sash, and a screen in said port.

6. A combined window and ventilator including a sash portion having an opening for passage of air, a screen in said opening, said sash having a channel portion formed in the body of the sash beneath the screen, a door, a deflector carried by the door and adapted to extend into and direct drainage into said channel portion, and means for exit of the drainage caught by said channel portion.

7. A combined window and ventilator including a sash portion having an opening for passage of air, a screen in said opening, said sash having a channel portion formed in the body of the sash beneath the screen, a door at the rear of the screen, and a deflector carried by said door, said deflector having a free end occupying a position downward and into said channel portion and being effective to cover a hinged joint between the door and the sash portion of the window.

HERMAN T. STELLJES.
